UNITED STATES PATENT OFFICE

138,594

DESIGN FOR AN OFFSET HAMMER SPUR FOR A PISTOL OR SIMILAR ARTICLE

Joe F. Jack, Arcadia, Calif.

Application June 12, 1944, Serial No. 113,966

Term of patent 7 years

(Cl. D30—1)

To all whom it may concern:

Be it known that I, Joe F. Jack, a citizen of the United States, residing in Arcadia, in the county of Los Angeles, State of California, have invented a new, original, and ornamental Design for an Offset Hammer Spur for a Pistol or Similar Article, of which the following is a specification, reference being had to the accompanying drawing, forming a part thereof.

Figure 1 is a side elevational view of an offset hammer spur embodying my novel design illustrating its relation to a revolver, the latter being shown in broken lines for illustrative purposes only.

Figure 2 is an enlarged side elevational view of the spur looking at the side opposite that shown in Figure 1.

Figure 3 is a top plan view of the spur.

Figure 4 is a cross sectional view of the spur taken on the line 4—4 of Figure 3.

Figure 5 is a cross sectional view of the spur taken on the line 5—5 of Figure 2.

Figure 6 is a bottom plan view of the spur.

I claim:

The ornamental design for an offset hammer spur for a pistol or similar article, as shown and described.

JOE F. JACK.
